UNITED STATES PATENT OFFICE.

GODFREY A. LYON, OF MIAMI, FLORIDA, AND RAYMOND W. ERWIN, OF FLUSHING, AND GEORGE W. HEISE, OF BAYSIDE, NEW YORK, ASSIGNEES, BY MESNE ASSIGNMENTS, TO NATIONAL CARBON COMPANY, INC., OF NEW YORK, N. Y., A CORPORATION OF NEW YORK.

CONTAINER FOR GRANULAR DEPOLARIZERS AND PROCESS OF MAKING THE SAME.

Application filed January 5, 1923. Serial No. 610,844.

This invention relates to improvements in galvanic cells having a granular depolarizing composition retained within a perforated container. The principal object of the invention is to provide convenient and effective means for preventing the granular composition from sifting out of the container during handling and storage prior to placing the cell in operation. In the preferred form of the present method, this object is attained by coating or lining the container with a sheet material adapted to be disintegrated by the electrolyte used in the cell.

The invention will be described in connection with the accompanying drawing, in which

Fig. 1 is a vertical central section through a galvanic cell provided with a lined receptacle for the depolarizing composition;

Fig. 2 is a perspective view of a paper-coated metal blank; and

Fig. 3 is a perspective view of a container having a removable wrapper.

Referring to Fig. 1, reference numeral 1 denotes a perforated container suspended by rod 2 from cover 3 and immersed in electrolyte 4. The invention is particularly applicable to copper oxid cells, and the structure illustrated is a commercial form of a cell of that type. Zinc electrodes 5 are provided and the container 1 is filled with granular copper oxid 6.

The container 1 is lined with a suitable material 7, preferably paper. The lining is applied to the container either as an adherent layer or by insertion of a paper bag or the like. The copper oxid is then filled into the container. By proceeding in this manner the objectionable sifting of the granular material through the container perforations, during handling and storage, is prevented.

The container, lining and depolarizer may be assembled in any suitable way. For example, a bag may be fitted into the container and the depolarizing composition then tamped in, or the copper oxid may be tamped into a bag, supported by a mold, and the filled bag may then be placed in the container. When the oxid is to be tamped into the lined container under considerable pressure, it is desirable to provide a removable supporting sleeve adjacent the lining to prevent the possibility of rupturing it.

As shown in Fig. 2, perforated sheet metal 8 may be covered with paper or the like 7 for use in making up the depolarizer containers. The paper may be readily applied by passing it with the metal between rollers, an adhesive being previously distributed over the surface of contact between the materials. The paper-coated metal may then be formed into containers in the usual manner. Lined containers may be conveniently made at low cost in the manner described.

We prefer to use relatively thin, unglazed paper. This is sufficiently strong to remain intact and prevent sifting of the depolarizer, but is readily disintegrated by the caustic electrolyte. After assembly of the cell there is no need for continued closure of the perforations and the removal of the closing means by disintegration, or the like, is desirable to permit unimpeded access of the electrolyte to the depolarizer.

According to another form of the invention, illustrated in Fig. 3, a removable wrapper 9 is provided. The wrapper may be made of heavy paper, cloth, or the like and is secured by means of adhesive strips 10, which retain it in smooth, firm engagement with the container. Strips 10 have projecting ends 11 which may be grasped to tear off the strips and permit the removal of the wrapping when the container is to be placed in electrolyte. Various other means for securing the paper or the like to the container may be adopted, provided they permit of ready removal of the secured material. The removable wrapper may be composed of a bag or carton, sheets cut to the proper size, or the like. It is generally preferable to remove the wrapper, but this is not essential unless it is made of material impervious to the electrolyte.

Aside from the advantage of retaining the depolarizer, the wrapping may also serve to protect the surface of the container, making it unnecessary to use iron which has been tinned or otherwise treated to prevent rusting. The cost of the container is thus reduced and a positive advantage is obtained by the elimination of tin and other coating metals detrimental to cell action.

We are aware that it has heretofore been proposed to fill the perforations in depolarizer containers with an electrolyte-soluble

material, to prevent sifting of the oxide, and that asbestos fabric has also been used for the same purpose. The present invention is distinguished from such prior processes by 5 the provision of a sheet lining removable mechanically or by the disintegrating action of the electrolyte. In this manner reliable protection against sifting is provided without materially increasing the internal resistance of the cell.

10 We claim:

1. A primary cell comprising a container, zinc and copper electrodes, and electrolyte, said copper electrode comprising a perforated copper container, a body of copper oxide therein and a protective member therefor comprising a layer of thin unglazed paper surrounding said copper oxide between said copper electrode and said copper 15 oxide, said paper being normally resistant to water and soluble in said electrolyte to 20

cause oxide and container to contact on putting in service.

2. A primary cell comprising a container, an electrolyte therein comprising a strong caustic solution, a zinc electrode therein, a copper electrode adapted to be positioned therein and comprising a perforated sheet copper container, a thin unglazed paper liner therefor having a substantial resistance 25 to moisture but adapted to be dissolved by said electrolyte, and a body of copper oxide within said copper container and separated therefrom by said paper prior to putting in service thereof.

30 In testimony whereof I affix my signature.

GOFFREY A. LYON.

35 In testimony whereof we affix our signatures.

RAYMOND W. ERWIN.
GEORGE W. HEISE.
